2,457,842

FREIGHT CONTAINER

Leathem D. Smith, deceased, late of Sturgeon Bay, Wis., by Alva F. Smith, administratrix, Sturgeon Bay, Wis., and Richard A. Stearn, Sturgeon Bay, Wis.; said Stearn assignor to Alva F. Smith, as administratrix of the estate of said Leathem D. Smith, deceased

Application October 4, 1946, Serial No. 701,102

11 Claims. (CL 220—1.5)

1

This invention relates to a shipping container. This application is a continuation in part of application Serial No. 592,376, filed May 7, 1945, by Leathem D. Smith, Richard A. Stearn and Carl R. Christianson, and of United States application Serial No. 610,148, filed August 10, 1945, by Leathem D. Smith, Carl R. Christianson, Richard A. Stearn and Howard H. Hunt.

The first object of this invention is to provide a shipping container of the type disclosed in copending application Serial No. 592,376, which has entrance doors at one end. In order to utilize a rigid container as contrasted with a collapsible container to its fullest extent, the entrance doors must be as high and as wide as possible. The construction shown in said copending application was not satisfactory for the installation of doors because the vertical corner structure was not sufficiently strong. These containers are to be lifted at their four upper corners and great rigidity is necessary. Additionally, the door construction must not interfere with the leg and socket construction. One of the features of this invention is the further development of the vertical side corner columns construction shown in Fig. 1 of said copending application. The folding leg, the vertically aligned socket or recess and the intermediate column are fabricated into substantially a single unit which are thereafter joined to transverse, top and beams, side walls, top and bottom to provide a very strong container open at one end.

The second object of this invention is to provide an improved leg socket and hook. The basic arrangement of this leg socket and hook is shown in Fig. 4 in copending application Serial No. 610,148, by Leathem D. Smith et al.

A third object of this invention is to provide an improved folding leg having a protected pin for locking the leg in either extended or retracted position. These containers are severely used. The retracting leg shown in copending application Serial No. 592,376, has a straight pin. This pin can be lost. One of the features of the present invention is the provision of a two-position pin permanently held in the leg mounting and projecting from the leg beneath the container. The pin is positioned so that it will not engage any part of the socket.

These and such other objects as may herein-after appear are attained in the embodiment of the invention shown in the accompanying drawing wherein:

Fig. 1 is a perspective view of the container showing the door end;

2

Fig. 2 is a front elevation of the container partly cut away to show means for fastening the side, bottom, top, to each other and to the corner panels;

Fig. 3 is a side view partly cut away for the same purpose;

Fig. 4 is a top view partly cut away to illustrate the construction;

Fig. 5 is a perspective view of an upper front door corner of the container showing a leg socket unit;

Fig. 6 is a view taken on the line 6—6 of Fig. 8;

Fig. 7 is a front view of a container leg unit; and

Fig. 8 is a side view of a container leg unit.

Continuing to refer to the drawings, applicants' container generally identified by the numeral 10, consists essentially of a strong floor or base 12, see Fig. 3, of rectangular plan configuration having a column mounted at each corner and having a beam connecting the tops of each pair of columns at each end. Referring to Fig. 1, the columns are designated by the numerals 14, 16, 18 and 20 not shown. The columns 14 and 16 are connected at their tops by a front beam 22 and the columns 18 and 20 by a rear beam 24. The columns 14 and 16 connected by the beam 22 constitute an inverted U-shaped frame, and the same is true of columns 18 and 20 joined by the beam 24. These inverted U-shaped members constitute the supports for the side walls 26 and 28, the top 30, the rear end wall (not shown) and the front doors 34 and 36.

Continuing to view the container generally, it will be noted in Fig. 1 that all of the closure panels carry outwardly directed reinforcing flutes 38. These flutes, however, do not extend beyond a plane containing the surface of adjacent columns, i. e., the surface 40 of the column 16 and 42 of column 18. The reason for this is that the load capacity of the containers is such and the desire to keep down the weight is such that reinforcing flutes are necessary; on the other hand, for stacking purposes, it is desirable that the external surfaces of the corner columns accurately define the plane dimensions of the container while the surfaces of the beams 22 and 24 define the top dimension of the container. At the same time it is desirable to have the flat surface of the side walls constitute the inner wall of the container because it is easier to arrange a load in a container when working against the flat walls as contrasted with ribbed walls. Referring to Fig. 4, it will be noted that the column 16 has an inwardly directed flange 48 which has approxi-

mately the same depth as the radius of a flute 38. Referring to Fig. 1, the corresponding flange 46 on column 18 is indicated and it will be noted that this flange continues on across the top of the container. A similar flange is on the vertical side edges of the other columns so as to similarly set back the front doors and the rear end wall.

Base and folding leg construction

Referring to Fig. 3, the base comprises a series of metal floor panels 48 having an L-shaped cross section with flanges 50 and 52 which are assembled into a flat flooring by welding at 54 and by side channel bars such as 56, see Fig. 2. The front of the flooring is closed in by a heavier channel beam 60 which is at the door end of the container.

Mounted on the four corners of the container are leg units, there being two left and two right leg units. Referring to Figs. 6, 7, and 8, a leg unit consists of a base plate 62, from the outside corner of which depends an apron 64 consisting of plates 66, 68, and 70. Disposed with its upper end inside the apron 64, is a folding leg generally identified by the numeral 72. This folding leg comprises a pair of side walls 74 and 76 joined together by a leg face 78. It will be noticed that the leg side walls 74 and 76 are beveled at 80 and that the top edge such as 82, is flush with the bottom of the plate 62. The effect is that when a weight is positioned on the plate 62 with the leg in the solid line position shown, the weight will be transmitted through the top edges 82 of the leg side walls 74 and 76 and the top edge of the leg face 78 to the leg 72.

The bevel 80 is the cord of an arc having 84 as its center and having the right angle "a" forming its radial limits. The plates 66 and 70 and the leg side walls 74 and 76 are perforated by like-size holes along an axis through the point 84. A pair of supporting, auxiliary plates 86 and 88 are similarly perforated. Equidistant from the hole, such as 90, are like-size holes 92 and 94. Holes in alignment with the hole 92 but in the plates 74, 86, 88, 76 and 70 are shown in Fig. 6. Holes aligned with the hole 94 in the plates 86, 88, and 70 are likewise there shown. At the same distance from a center 84 but in the two leg side walls 74 and 76 are aligned openings such as 96. Positioned through the openings aligned with the hole 90 is a locking pin 98 having two offset shanks 100 and 102 for engaging the sets of holes in alignment with hole 92. A spring 104 having one end seated in an annular recess 106 in a collar on the locking pin 98 urges the pin into the position shown in Fig. 6 where a shoulder 107 engages the plate 86. By inserting a lever at point 108, the pin may be retracted into dotted line position 110, thereby permitting the leg to be swung in the dot-dash line position 112. In order to lock the leg in this position, the locking pin is rotated 180 degrees so that it may now drop into those holes in alignment with the hole 94. It will be noted that the locking pin cannot be removed by ordinary usage, so that it will not get lost, and that its head is on an inside of the leg where it is not so likely to catch some object and be damaged. It will also be noted, referring to the upper left-hand leg recess in Fig. 2, that the outer edge of the locking pin 98 is at a point more distant from the bottom of the leg than the depth of the socket so that in maneuvering a leg into a socket, the pin cannot be damaged.

Returning to Fig. 8, when the leg is in folded position, it may also act as a leg because of a

portion 116. The hole 90 is to the left of a line bisecting this portion 116 of this leg and consequently there will be no tendency of the leg to change position. Whether the leg is in the upright position or raised position, any weight on the plate 62 will be transmitted to the leg not by way of pins through holes 90, 92, and 94 but by way of the upper edges of side walls and leg face 14, 16, and 78 or by way of the side edges 120 of the plates 74 and 76, which engage the bottom of the base 62.

The foregoing description covers a right-hand leg. The left-hand leg is the reverse of the right-hand leg. There are two left-hand and two right-hand legs and the base is welded to the plates such as 62 and, as illustrated in Figs. 2 and 3, are set back a short distance from the corners.

The inverted U-shaped frames

The column 16 is a vertical right angled member comprising two side walls 122 and 124 bent over a rounded corner at right angles to each other. Vertical edges of the column 16 are turned 180 degrees inwardly to form reverse flanges 126 and 128. The long and short dimensions, in cross section, of the column 16 are the same as long and short dimensions of a leg recess base plate 130, see Fig. 5, and which is butt-welded around its edges to the top of the column 16. The leg recess comprises the sloping surface 132 which meets the base plate 130 at the same angle as does, referring to Fig. 2, the inside slope 134 of a leg 136. Returning to Fig. 5, the surface 138 is canted with respect to the base plate 130 for guiding a leg of a superposed container into proper position. The surface 138 is broken by a draw which is segregated by a bridge 142. The purpose of the draw 140 and the bridge 142 is to permit a hook from a crane or an especially adapted lifting rig to grip a corner of the container at the socket. This is fully disclosed in copending application Serial No. 610,148. The leg recess is at present fabricated by cut plates and welding, conceivably a casting might be used. In this invention, it constitutes the capital of a column, and the column 16 and the leg recess unit provide great rigidity.

The two front columns with their recess unit capitals are joined by the horizontal beam 22, 50 which referring to Fig. 3, is seen to consist of a top plate 146 having a downwardly reversed flange 44, a rounded lintel 150 and an inside reinforcing gusset 152.

The inverted U-shaped front frame is mounted on the base by resting the bottoms of the columns 14 and 16 on the leg base plates such as 62 and then welding the columns' bottom to the base plates and the flanges to the side of the base itself.

The rear inverted U-shaped frame is constructed in the same manner as the front excepting that the cross beam 24 has a vertical reinforcing gusset not shown, of slightly different shape from 152.

Side walls, top, rear end, and front doors

The closure panels may be quickly described. Essentially they consist of rectangular units with outwardly rolled flutes which are welded along their edges either to the sides of the base or to the reverse flanges of the column. Thus referring to Fig. 2 and Fig. 4, side wall 26 is welded to the inside surface of the flange 126. The same is true of the top, the other side wall, and the back with respect to the flanges on the adja-

cent beam or column. At the point where the side walls meet the top, a rolled angle iron is used, see Fig. 2, where the angle iron bears the numeral 162. The angle iron is applied to the inside edge of the side wall and top.

It will be appreciated that it makes it possible to use nuts and bolts so that the container may be constructed so that it can be erected and taken apart. Under such circumstances the elements of the container will consist of the two U-shaped members, the base with leg attached, and the side, end, and top panels, and the front doors.

The front doors 34 and 36 are complementary with the right-hand door overlapping the left-hand door 34. Two hinges such as 164 and 166 are used and any appropriate latch such as 168. Levers 170 and 172 control auxiliary locking bolts, not shown. In Figs. 3 and 4 the parametric construction of the doors is illustrated. The doors sit well inside of the faces of the column.

Having thus described our invention, what we claim is:

1. A fabricated metal freight container having a right parallelepiped shape comprising a rectangular bottom, a column vertically mounted on the bottom at each corner thereof, a leg pivotal around a horizontal shaft mounted on the bottom in vertical alignment with each column, two bases on each leg angularly spaced from each other with respect to the shaft and each in the same vertical line when in effective position, one base being at a greater distance from the shaft than the other base, each base being spaced from the container bottom when in effective position, an upwardly open leg socket rigidly mounted on the top of each column in vertical alignment with whichever depending leg base is in effective position, side walls on said sockets which cooperatively engage either base of the legs of a superposed similar container and hold the legs and the container against lateral movement in any direction, side walls joining the columns and their superposed leg sockets to each other, and a top joining the top edges of the side walls and the top of the leg sockets to each other.

2. A freight container having a right parallelepiped shape comprising a rectangular bottom, a column vertically mounted on the bottom at each corner thereof, a pair of spaced, vertical plates rigidly fastened to the bottom beneath each column, a leg having its upper portion positioned between said plates, axially aligned holes through said plates and leg, an axially movable shaft disposed in said holes, two bases on each leg angularly spaced from each other with respect to the shaft, one base being at a greater distance from the shaft than the other, and each base being spaced from the container bottom when in effective position, aligned holes through one plate and a portion of said leg parallel to the shaft, a second shaft in the latter holes and rigidly connected to the first shaft at a point outside the plate, an upwardly open leg socket rigidly mounted on the top of each column in vertical alignment with the depending leg, side walls on said sockets which cooperatively engage the legs of a superposed similar container and hold the legs and the container against lateral movement in any direction, side walls joining the columns and their superposed leg sockets to each other, and a top joining the top edges of the side walls and the top of the leg sockets to each other.

3. A freight container having a right parallelepiped shape comprising a rectangular bottom, a column vertically mounted on the bottom at each

corner thereof, a leg mounted on the bottom in vertical alignment with each column, an upwardly open leg socket rigidly mounted on the top of each column in vertical alignment with the depending leg, side walls on said sockets which cooperatively engage the legs of a superposed similar container and hold the legs and the container against lateral movement in any direction, an upwardly open slot extending from the socket sidewall to the container top, a bridge across the slot at the intersection of the socket side wall and the top to form a recessed eyelet, side walls joining the columns and their superposed leg sockets to each other, and a top joining the top edges of the side walls and the top of the leg sockets to each other.

4. The container of claim 3 wherein the width of the eyelet slot is less than any horizontal dimension of a leg base.

5. A freight container comprising a body having a top, bottom, and side walls, a plurality of depending legs mounted on the body bottom, a like plurality of upwardly open leg sockets for seating similar legs in another container mounted in the upper part of said container and each in vertical alignment with a depending leg, side walls in said sockets which cooperatively hold the legs of a superposed similar container from lateral movement in any direction, an upwardly open slot connecting the side wall of each socket to an adjoining portion of the top, and a bridge across the slot to form a lifting eyelet.

6. A fabricated metal freight container comprising a generally rectangular bottom, an elongated plate having a longitudinal bend mounted vertically with the outer side of the bend at each corner to form a corner column, a leg depending from the bottom beneath each corner column, a horizontal leg rest plate welded to the upper end of each column at the bend and extending inwardly of the column to all points in vertical alignment with the bottom of the associated leg, guide walls attached to and extending upwardly from the inside edges of each rest plate to form open-sided leg sockets, side walls fastened to and joining the edges of adjacent columns and guide walls, and a top fastened to the top edges of the side walls and guide walls so that the horizontal leg rest plate and its associated guide walls are recessed into the container inside the planes of the container side walls and top.

7. A fabricated metal freight container comprising a generally rectangular bottom, an elongated plate having a longitudinal bend mounted vertically with the outer side of the bend at each corner to form a corner column, a leg depending from the bottom beneath each corner column, a horizontal rectangular leg rest plate welded along two sides to the upper end of each column at the bend and extending inwardly to all points in vertical alignment with the bottom of the associated leg, a guide wall attached to one inside edge of the leg rest plate and extending upwardly and inwardly, a second guide wall attached to the other inside edge of the leg rest plate and extending upwardly and inwardly, side walls fastened to and joining the edges of adjacent columns and guide walls, and a top fastened to the top edges of the side walls and guide walls so that the horizontal rectangular leg rest plate and associated guide walls are recessed into the container and inside the planes of the container side walls and top.

8. A fabricated metal freight container comprising a rectangular bottom, a leg depending

from each corner of the bottom, a metal column having a generally right angle cross section mounted at each corner of the container with the bend outward, an upwardly open leg socket unit having a bottom plan configuration symmetrical with the cross section of the top of the column rigidly welded by its bottom edges to the top edge of the column, said socket unit being of a size capable of seating a similar leg of another container and being in vertical alignment with the leg associated with the column, side walls fastened to and joining edges of adjacent columns and superposed socket units, and a top fastened to the top edges of the side walls and socket units so that the socket units are recessed inside the planes of the side walls and top.

9. A fabricated metal freight container comprising a rectangular bottom, a pair of U-shaped frames invertedly and rigidly mounted on two opposite sides of the bottom with the frame ends at the corners, a leg mounted on the bottom beneath each frame end, a leg socket having a horizontal leg rest plate and inside upwardly directed guide walls forming an open-sided leg socket recessed into the outside face of each frame at each upper corner so that the leg rest plate is in vertical alignment with the associated depending leg, and side walls and top rigidly joining the inverted U-shaped frames to each other.

10. A fabricated metal freight container comprising a rectangular bottom, a pair of U-shaped frames invertedly and rigidly mounted on two opposite sides of the bottom with the frame ends at the corners, a leg mounted on the bottom beneath each frame end, a leg socket having a horizontal leg rest plate and inside upwardly directed guide walls forming an open-sided leg socket recessed into the outside face of each frame at each upper corner so that the leg rest plate is in vertical alignment with the associated depending leg, an inwardly directed flange formed along the edges of the frames that face each other, side walls and a top fastened to the inside edges of said flanges, and external reinforcing members on said side walls and top lying inside planes containing the side and top surfaces of the U-shaped frames.

11. A fabricated metal freight container comprising a rectangular bottom, a pair of U-shaped frames invertedly and rigidly mounted on two opposite sides of the bottom with the frame ends at the corners, a leg mounted on the bottom beneath each frame end, a leg socket having a horizontal leg rest plate and inside upwardly directed guide walls forming an open-sided leg socket recessed into the outside face of each frame at each upper corner so that the leg rest plate is in vertical alignment with the associated depending leg, an inwardly directed double bend flange formed along the edges of the frames that face each other, and side walls and top rigidly fastened to the inside surface of the second bend of said flanges.
